UNITED STATES PATENT OFFICE.

JOHN M. CAGE, OF SANTA MONICA, CALIFORNIA.

CONDENSER.

Application filed September 26, 1921. Serial No. 503,342.

To all whom it may concern:

Be it known that I, JOHN M. CAGE, a citizen of the United States, residing at Santa Monica, in the county of Los Angeles and State of California, have invented new and useful Improvements in Condensers, of which the following is a specification.

This invention relates to ignition systems for internal combustion engines, such as automobile and aviation engines, or all types of internal combustion engines that use a high tension system of ignition. It will be readily understood that, although I describe my invention particularly as adapted to automobile engines, the invention is not in the least limited to engines that are used for such purposes.

There are many objects of this invention, and the objects and the corresponding accomplishments will be best understood from the following detailed description of typical forms of my system and typical forms of my condenser, but it may be well to state some of the general objects and features of the invention before proceeding to such detailed description.

I have found by trial and experimentation that the energy of the present ignition system is not efficiently concentrated at the spark gap; apparently only a fraction of the energy of the system being delivered at the spark gap in the form of a spark for igniting the combustible gases. My invention includes, and revolves about, my discovery of the fact that by placing a suitable condenser, of suitable capacity, in parallel with the spark gap, I am able to very greatly increase the energy of the resultant spark without increasing the amount of energy necessary to operate the system, and thus without increasing the pull of energy on the battery. During the time that the secondary circuit of the ignition system is in operation, this condenser is charged, and then immediately discharges, in a series of oscillations, across the spark gap; delivering to the spark gap the energy which it has temporarily stored, in addition to the energy which, by the normal operation of the system, would reach the spark gap.

I have found that, in order to obtain effective results with my system, it is necessary that the condenser be properly proportioned, in point of capacity, to the capacity of the remainder of the system. This is particularly true where the system also con-

tains a primary condenser, and where the induced current in the secondary circuit is caused by oscillations in the primary circuit from the primary condenser. In such a case it is desirable that the secondary condenser be of such capacity that the capacity of the thus formed secondary circuit, and its inductiveness, shall bear such a relation to the capacity and inductiveness of the primary system, that the oscillations in both circuits shall be capable of moving substantially in unison, thus tending each to amplify the other rather than each to damp out the other.

I will give further details first regarding the system and its operation and regarding the specific preferred form of conception of condenser in the following detailed specification, reference for this purpose being had to the accompanying drawings, in which:—

Fig. 1 is an exterior view of one form of condenser used by me in a typical ignition system; Fig. 2 is a longitudinal central section of the same; Fig. 3 is a cross section of the same; Fig. 4 is a diagram of a typical ignition system illustrating the place of my condenser in that ignition system; Fig. 5 is an exterior view of another form of condenser adapted particularly for application to the ignition systems of Ford cars; Fig. 6 is a longitudinal central section of the same; Fig. 7 is a transverse section of the same; and Fig. 8 is a diagram illustrating the ignition system of a Ford car and illustrating the placement of my condenser in that system.

I shall refer first to the form of device shown in Figs. 1 to 4, which is the form of device applicable to meet present day automobile ignition systems. In applying my condenser to an ignition system of the character here illustrated, it is only necessary to secure the condenser in some suitable manner to any supporting part of the automobile and then connect one of its wires to a ground and connect the other one of its wires to the single high tension wire that leads from the high tension coil to the center of the high tension distributor. The condenser having been properly designed for the system, and having been properly connected in the manner above described, the whole system is then ready for operation. In Fig. 4 I indicate at E an engine cylinder block with its several spark plugs S connected by wires 10

to the contacts 11 of the distributor head 12, the central contact 13 of which is connected by high tension wire 14 to one end of the secondary coil 15. The other side of the 5 secondary coil 15 is connected to wire 18. The primary winding 17 of the coil is connected by wire 18 to one side of the battery B which is connected at 19 to ground at the other side; the other side of primary winding 10 17 being connected by wire 20 to the primary breaker 21 whose other side is connected at 22 also to ground. The primary condenser 23 is connected by wires 24 and 25 around the breaker 21. The action of this 15 simple form of ignition system is well known. Upon breaking of the current at the breaker 21, not only is the current induced into secondary coil 15, but also by inductive action, the condenser 23 is charged. 20 As soon as the condenser is charged, it immediately discharges around through the primary 17; and the oscillatory nature of the discharge causes a high tension induced current to flow in secondary 15 and through 25 the secondary circuit to the spark plugs.

My condenser V is connected by one wire 30 to the main high tension wire 14 and by another wire 31 to a ground connection; being, in essence, connected into the high tension circuit around the spark gaps. In so connecting my condenser into this circuit it will be seen that I immediately add capacity to the circuit; and the capacity which I add is gauged to be such as to cause the sum total 35 capacity of the secondary circuit, and its inductiveness, to be in such proportions and bear such relations to each other as causes the period of oscillation in the high tension secondary to be substantially in step with 40 the period of oscillation in the low tension primary. In other words, when oscillations are passing through the primary circuit, and are inducing corresponding currents in the secondary circuits, then, in my system, the 45 oscillatory frequency of the secondary circuit is such that the oscillations set up in the secondary circuits tend to amplify and augment the oscillations in the primary, and thus to increase the efficiency of the system 50 as a whole rather than tend to damp off the oscillations in the primary.

I provide a condenser of the proper capacity in a very simple and comparatively inexpensive form; made up so as to be small 55 in compass in comparison with its electrostatic capacity; and in such form and construction as is not apt to be deteriorated, disarranged, or broken by any of the influences to which it may be subjected in an 60 automobile.

In providing a condenser to accomplish these purposes, I provide a suitable case 40, shown in this particular instance to be made out of wood. The body of this case may 65 easily be made in two halves 40^a and 40^b,

each half having a semi-cylindrical groove in it, so that when the halves are laid together they form a case with a cylindrical opening. This cylindrical opening is closed by end caps 41. The drawings show the device in full size as used on the average automotive ignition system. A cylindrical glass tube 42 is centrally located in the cylindrical interior of the case, being bonded in and supported by a filling of petrolastic cement (a comparatively fine grade of tar which is made especially for use in connection with storage batteries) indicated at 43. This filling has a melting temperature high enough that it will not melt and run, or soften sufficiently to allow the glass tube or other parts to become displaced at the highest temperature reached in the atmosphere around the engine of an automobile. For instance, the melting temperature of the tar which I now preferably use is about 175° Fahrenheit.

Inside the glass tube there is a cylindrically bent sheet of metal, as illustrated at 44, and outside the glass tube there is a similar bent sheet of metal, as illustrated at 45. These sheets are preferably not seamless tubes, but are made by rolling up steel shim stock about .002 of an inch thick; the outer sheet being rolled tightly enough that it will grip the outside of the glass tube and the inner one being rolled openly enough that it will expand against the inside of the glass tube. Around the outside condenser plate thus formed a wire 46 is wound two or three times and then twisted to hold it tightly in place, and the grounding wire 47 of the condenser is connected to this wire 46. Inside the glass tube there is placed a "hair-pin" 48 made of steel piano wire of about the shape illustrated in Fig. 2 and with ends that are substantially parallel, and the "hair-pin" having sufficient outward resiliency so that the ends press outwardly against the central portions of the inner plate 45 to press it out against the inner face of the tube 42. The inner end of the high tension wire 48 is connected at 49 to the upper part of the "hair-pin." The "hair-pin" thus performs the office of pressing the inner plate out against the glass tube and also of making electrical connection to the inner plate. High tension wire 48 extends out through the same end cap 41 as does the ground wire 47. It will be noted that the two plates 44 and 45 are of lesser length than the glass tube, sufficient excess length of the glass tube being thus provided to prevent leakage around the end. The glass tube is preferably of the quality known as pyrex glass. This quality of glass has a high dielectric coefficient and is substantially immune from breakage or fracture due to any reasonable changes of temperature. I find it very satisfactory for

use in my condenser. In the size of condenser herein described, the plates are each approximately seven square inches area. Of course, any suitable material may be used 5 for these plates but I find steel shim stock suitable for this purpose as it is of smooth surface and can be had in uniform thin thicknesses and rolls very evenly.

After experimenting with a large number 10 of dielectrics for separating the plates and for filling the space between them and the case and for covering the exposed portions of the glass and plates to prevent "brushing" I have found this combination of 15 glass and petrolastic cement to be most highly efficient. The tar cement has a sufficiently high dielectric co-efficient, possesses a sufficient rigidity to hold the parts in place, and at the same time has the very 20 desirable quality of preventing "brushing" because it has an adhesive quality both to the metal and to the glass that prevents its being raised from the metal and glass by the electric action. Paraffine, for instance, 25 I find is comparatively easily raised from the glass by the electric action, forming a thin open space in which "brushing" takes place. This is not true of the adhesive tar. Furthermore, the tar has all the advantage 30 of a solid although it can be poured into the container while in liquid form, and has none of the disadvantages of a liquid. I have found in using a liquid dielectric that if on any occasion an arc or local heating 35 takes place, a gas bubble or bubbles will be formed which immediately causes current leakage. This does not take place in the tar.

In assembling this condenser the two 40 sides of the box are glued together and one end glued and nailed on. Then the entire assembly of glass tube, the two plates, and the wire connections, etc. having been previously put together, is inserted in the container with the wires 47 and 48 projecting. Tar is then poured in at a temperature high 45 enough to keep it liquid, care being taken that the tar does not boil, in order to avoid any bubbles being formed in the finally 50 solidified tar. Usually two or three separate pourings of the tar are necessary in order to fill the container completely to the top. The cap is then put in place preferably being glued and nailed. The finished 55 box may be provided with any suitable mounting means. For instance, I may provide a pair of bolts 50 that project through the two halves of the box, these bolts thus providing means for holding the box together and also for mounting them on a suitable part of the automobile.

In Figs. 5 to 8, I have shown a similar form 60 of condenser which embodies four units in one casing, and particularly adapted to such ignition systems as are used on the Ford

automobile. Here I show a metal container 60 with a cap 61 that is put into place as the parts are assembled. This container being most conveniently suspended on the radiator stay rod, I provide the container 70 60 with a pair of wire clips 62 that may be easily bent around the stay rod to support the container. Container 60 is in this case preferably cylindrical and it contains four sets of condenser elements 63, each 75 like the condenser element hereinbefore described, in that it is made up of a glass tube 64, outer and inner plates 65 and 66, and a high tension wire connection 67 connected to the inner plate in the manner 80 hereinbefore described. There are four such high tension wire connections, each leading out through the end cap 68. For this purpose the end cap is perforated as shown at 85 69, and a rubber or fibre or other suitable perforated washer 70 is placed inside the end cap as illustrated; the washer 70 being made of insulating material, and the perforations 69 in the end cap 68 being sufficiently large to space their edges from their 90 various wires. There is only a single ground wire 71, and this single ground wire leads up between the four container elements and is connected to the wire 46^a 95 that is wound around all four of the condenser elements and is thus wound around in contact with all four of the outer plates 65. How this is accomplished can be clearly seen from the drawings. Thus we have a condenser, made up similarly to that hereinbefore described, but having four independent high tension outlets and one common 100 ground wire. The interior of this condenser is filled with the same tar material as hereinbefore described. For the ignition system 105 of Fords the capacity and dimensions of each condenser element is approximately the same as for the standard apparatus hereinbefore described. In each case the plates have an area of an average of about seven 110 square inches (this can be varied somewhat and still get good results); the glass is of the quality known as pyrex and has a thickness of about 1.5 millimeters. The drawings show both types of condenser substantially 115 in full size.

The system of connections of this condenser into the Ford ignition system is shown in Fig. 8. Here the battery is indicated at B one side of which is grounded as at 80, and 120 the other side of which is connected by wire 81 and 82 to one side of the primary windings 83 of the four induction coils. The other side of each primary winding 83 is connected through the coil vibrator and by 125 individual wire 84 to an individual contact 85 on the timer T, the central contact of which is connected as shown at 86 to ground. The secondary winding 87 of each induction coil is connected by individual wire 88 130

to the spark plugs S of the engine E. The primary circuit condensers 23 are connected by wires 90 to one side of the primary windings and by wires 91 and 92 to ground. The 5 ground wire 71 of my condenser V is connected to ground as indicated, while the four high tension wires 67 are connected individually to the four wires 88 that lead to the spark plugs. Without the necessity of following out the circuitings here it will be seen that the condenser V occupies the same position with relation to the spark gaps that it occupies in the form shown in Fig. 4; the 10 only difference here being that there is one condenser unit for each spark plug whereas in Fig. 4 there is one condenser unit for all the spark plugs.

Having described a preferred form of my invention, I claim:

- 20 1. A condenser embodying a container, a dielectric tube therein, a resilient conductor plate inside the tube springing out against it, a resilient conductor plate outside the tube resiliently clasping it, and a filling for the container of dielectric material which is adhesive to the tube and plates and solid at ordinary temperatures to support them in the container.
- 25 2. A condenser embodying a container, a dielectric tube therein, a resilient conductor plate inside the tube springing out against it, a resilient conductor plate outside the tube resiliently clasping it, a resilient hair

pin inside the tube pressing out against the inner plate, a conductor connected to the hair 35 pin, a wire wound around the outer plate, a conductor connected to the wire, and a filling of dielectric material for the container solid at ordinary temperatures to support the tube and plates in the container. 40

3. A condenser embodying a container, a dielectric tube therein, a resilient conductor plate inside the tube springing out against it, a resilient conductor plate outside the tube resiliently clasping it, a resilient hair 45 pin inside the tube pressing out against the inner plate, a conductor connected to the hair pin, a wire wound around the outer plate, a conductor connected to the wire, and a filling of dielectric material for the container solid at ordinary temperatures to support the tube and plates in the container, 50 said material being adhesive to the plates and tube.

4. A condenser embodying a container, a dielectric tube therein, a resilient conductor plate inside the tube springing out against the inner surface of the tube, a resilient conductor plate outside the tube and resiliently 55 springing in against the outer surface of the 60 tube, and a dielectric filling for that container inside and outside the tube.

In witness that I claim the foregoing I have hereunto subscribed my name this 8th day of September, 1921.

JOHN M. CAGE.
